UNITED STATES PATENT OFFICE.

FREDERICK C. SEBULSKE, OF DETROIT, MICHIGAN, ASSIGNOR TO SUNNY LINE APPLIANCES, INCORPORATED, OF DETROIT, MICHIGAN, A CORPORATION OF DELAWARE.

DESIGN FOR A WASHING-MACHINE FRAME.

60,430.

Specification for Design.

Patented Feb. 14, 1922.

Application filed January 31, 1921. Serial No. 441,435. Term of patent 14 years.

To all whom it may concern:

Be it known that I, FREDERICK C. SEBULSKE, a citizen of the United States, and residing at Detroit, county of Wayne, and State of Michigan, have invented a new and original and ornamental Design for Washing-Machine Frames, of which the following is a specification, reference being had to

the accompanying drawing, forming part thereof.

The figure is a perspective of a washing machine frame showing my new design.

I claim:

The ornamental design for a washing machine frame, as shown.

FREDERICK C. SEBULSKE.
